DOUBLE-TWIST SPINDLE

Otto Bochmann, Remscheid-Lennep, Germany

Application November 7, 1952, Serial No. 319,355

Claims priority, application Germany August 19, 1950

17 Claims. (Cl. 57—58.83)

The present invention relates to double twist spindles. 15
The present application is a continuation-in-part of
U. S. patent application serial No. 241,850, filed on
August 14, 1951 and entitled "Double-Twist Spindles."

In the above referred to application, there is a double-twist spindle in which a ring-shaped member for guiding the thread is located between two core members which are surrounded by a tubular member. When it is necessary to change the ring-shaped member, because of breakage or wear of the same, for example, it is necessary to disassemble the core members from the tubular member and to reassemble the same with a new ring-shaped member. This assembly and disassembly of these parts creates an undesirable inconvenience.

It is accordingly an object of the present invention to overcome this inconvenience by providing a construction where the ring-shaped member is removable from the parts supporting the same while these parts remain assembled.

A further object of the present invention is to provide an apparatus of the above type with a means for supporting the ring-shaped member in such a way that it may be removed from and inserted into its supporting structure from two different parts thereof.

Still another object of the present invention is to provide a means for wedging the above referred to core members and tubular member to each other.

A still further object of the present invention is to provide a means for removably supporting a ring-shaped member of the type referred to above, in such a way that no fastening members are required to hold the ring-shaped member and no parts other than the ring-shaped member are required to be moved during replacement of the latter.

With the above objects in view, the present invention mainly consists of a double twist spindle apparatus which includes a first elongated spindle core member formed with a bore extending therethrough along its axis; a second elongated spindle core member coaxial with said first core member and being located apart from the same to form a space between said first and second core members, said second core member having an end portion located adjacent said first core member and formed with at least one cutout extending into said second core member and opening onto the end surface of said end portion thereof; a tubular support member embracing said first and second core members and supporting the same, said tubular member being formed with at least one slot passing through the wall thereof and being aligned with said cutout of said second core member, said slot having an end portion extending beyond said cutout and opposite said space between said first and second core members, and said end portion of said slot being of a larger size than said cutout; and a centrally apertured ring member mounted in said tubular member in said space between said first and second core members, the aperture of said ring member being aligned with said bore of said first core member and overlapping said cutout of said second core member so that a thread may be guided through said bore of said first core member, through said aperture of said ring member, through said cutout of said second core member and through said slot of said tubular support member, said apertured ring member having a cross section smaller than said end portion of said slot so as to be insertable into and removable from said space between said core members through said end portion of said slot.

5 The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings, in which

Fig. 1 is a vertical sectional view of an apparatus constructed in accordance with the present invention;

Fig. 2 is a fragmentary elevational view, on an enlarged scale, of a part of the structure of Fig. 1;

Fig. 3 is a sectional view taken along line 3—3 of Fig. 2 in the direction of the arrows;

Fig. 4 is a sectional view taken along line 4—4 of Fig. 3 in the direction of the arrows.

Referring to the drawings, there is shown a spindle core member 1 which is bored along its axis at 5 and a spindle core member 2 which is provided with two sector shaped cutouts in the end portion thereof located adjacent to the spindle core member 1. The spindle core members 1 and 2 are spaced from each other fixedly mounted in a tubular member 3 so as to be supported thereby. As is clearly apparent from Figs. 2 and 3, the parts 1, 2, and 3 are conical so that the core members 1 and 2 may be fixed to the tubular support 3 by being tightly wedged thereto. The tubular member 3 is provided with two slots 7 which are aligned with the cutouts in the upper end portion of the spindle core member 2 (Fig. 4). As is apparent from the drawings, the upper end of portion 18 of slot 7 has an enlarged circular shape and overlaps both the core members 2 and 3 while extending across the space therebetween. Located between the spindle core members 1 and 2 is the ring-shaped member 6 which may be made of steel, which may be chrome plated, or of a ceramic material or of porcelain. This ring-shaped member 6 has a central aperture aligned with bore 5 and overlapping the cutout of spindle core member 2, the end of this aperture located adjacent to core member 1 being smaller than the opposite end of the aperture located adjacent to core member 2, and the aperture being smoothly curved between the ends thereof. The ring-shaped member 6 is provided with a smooth surface at least at the aperture thereof, and the member 6 is of a rectangular shape and of a width smaller than the width of circular end portion 18 of slot 7. As is apparent from Fig. 2, the side edges of the ring-shaped member 6 frictionally engage the tubular support 3 in each of the cutout portions 18 thereof along four lines, and this friction is sufficient to hold member 6 in position while permitting the same to be easily removed and replaced simply by being moved to the right or left, as viewed in Fig. 3. It is apparent that no special fastening means need be applied or removed during replacement of a member 6, and that the parts 1, 2 and 3 may remain in their assembled relationship during replacement of the member 6.

The tubular support member 3 is mounted on the member 8 which has two or more cut away portions 8a located between parts 8b and 8c of member 8 and aligned with the slots 7 of tubular member 3. As is evident from Fig. 1, part 8b of member 8 overlaps member 6 so that the latter cannot fly out through end portion 18 of slot 7 during rotation of the apparatus. Also, if desired, the width of cut away portions 8a may correspond to that of slots 7 to further prevent flying out of ring 6, and in this latter event the member 8 must be completely separated from member 3 and the parts carried thereby to allow ring 6 to be removed and replaced. Mounted above the member 8 is the dish-shaped member 9 which has a hollow central projection in which the ball bearing 11 and the roller bearing 10 are mounted, as shown in the drawing. These bearings interconnect the dish-shaped member 9 with the spindle core member 1, and the ball bearing 11 is mounted directly above the tubular support member 3.

75 The operation of the structure illustrated in the drawing is believed to be evident. The dish-shaped member 9 is intended to remain substantially stationary and to support the spool of thread to be twisted on the central projection thereof, while the parts 1, 2, 6, and 8 all rotate together. The thread 4, from a spool (not shown)

mounted on the central projection of dish-shaped member 9, passes through the bore 5 of spindle core member 1, through the central aperture of ring-shaped member 6, through a cutout of spindle core member 2, through a slot 7 of tubular member 3, and through one of the cut away portions of the member 8. This latter path for the thread to be twisted forms a conduit means for the thread, and the smoothly curved aperture of ring-shaped member 6 provides a smooth surface at the sharp bend in the conduit means so that a minimum of wear is caused on the thread to be twisted. In other known devices of this type, the thread must pass over a relatively sharp corner at the bend in the path through which it moves, and this sharp corner causes damage and wear on the thread to be twisted. These latter defects and disadvantages are completely eliminated by the structure described above, and in particular by ring-shaped member 6.

It will be understood that each of the elements described above, or two or more together, may also find a useful application in other types of double twist spindles differing from the types described above.

While the invention has been illustrated and described as embodied in double twist spindles having a removable device for reducing to a minimum the wear on the thread to be twisted, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be secured by Letters Patent is:

1. In a double twist spindle, in combination, a first elongated spindle core member formed with a bore extending therethrough along its axis; a second elongated spindle core member coaxial with said first core member and being located apart from the same to form a space between said first and second core members, said second core member having an end portion located adjacent said first core member and formed with at least one cutout extending into said second core member from the end and side faces thereof adjacent said first core member; a tubular support member embracing said first and second core members and supporting the same, said tubular member being formed with at least one slot passing through the wall thereof and being aligned with said cutout of said second core member, said slot having an end portion extending beyond said cutout and opposite said space between said first and second core members, and said end portion of said slot being of a larger size than said cutout; and a centrally apertured ring member mounted in said tubular member in said space between said first and second core members, the aperture of said ring member being aligned with said bore of said first core member and overlapping said cutout of said second core member so that a thread may be guided through said bore of said first core member, through said aperture of said ring member, through said cutout of said second core member and through said slot of said tubular support member, said apertured ring member having transverse to a line extending across said ring member and through said end portion of said slot cross sections which are all smaller than said end portion of said slot so that said ring member is insertable into and removable from said space between said core members through said end portion of said slot.

2. In a double twist spindle, in combination, a first elongated spindle core member formed with a bore extending therethrough along its axis; a second elongated spindle core member coaxial with said first core member and being located apart from the same to form a space between said first and second core members, said second core member having an end portion located adjacent said first core member and formed with at least one cutout extending into said second core member from the end and side faces thereof adjacent said first core member; a tubular support member embracing said first and second core members and supporting the same, said tubular member being formed with at least one

slot passing through the wall thereof and being aligned with said cutout of said second core member, said slot having an end portion extending beyond said cutout and opposite said space between said first and second core members, and said end portion of said slot being of a larger size than said cutout; and a centrally apertured ring member mounted in said tubular member in said space between said first and second core members, the aperture of said ring member being aligned with said bore of said first core member and overlapping said cutout of said second core member so that a thread may be guided through said bore of said first core member, through said aperture of said ring member, through said cutout of said second core member and through said slot of said tubular support member, said apertured ring member having transverse to a line extending across said ring member and through said end portion of said slot cross sections which are all smaller than said end portion of said slot so that said ring member is insertable into and removable from said space between said core members through said end portion of said slot, and said ring member having a thickness which is smaller than the distance between said first and second core members.

3. In a double twist spindle, in combination, a first elongated spindle core member formed with a bore extending therethrough along its axis; a second elongated spindle core member coaxial with said first core member and being located apart from the same to form a space between said first and second core members, said second core member having an end portion located adjacent said first core member and formed with at least one cutout extending into said second core member from the end and side faces thereof adjacent said first core member; a tubular support member embracing said first and second core members and supporting the same, said tubular member being formed with at least one slot passing through the wall thereof and being aligned with said cutout of said second core member, said slot having an end portion extending beyond said cutout and opposite said space between said first and second core members, and said end portion of said slot being of a larger size than said cutout; and a centrally apertured ring member mounted in said tubular member in said space between said first and second core members, the aperture of said ring member being aligned with said bore of said first core member and overlapping said cutout of said second core member so that a thread may be guided through said bore of said first core member, through said aperture of said ring member, through said cutout of said second core member and through said slot of said tubular support member, said apertured ring member having transverse to a line extending across said ring member and through said end portion of said slot cross sections which are all smaller than said end portion of said slot so that said ring member is insertable into and removable from said space between said core members through said end portion of said slot, and said ring member having a thickness which is smaller than the distance between said first and second core members.

4. In a double twist spindle, in combination, a first elongated spindle core member formed with a bore extending therethrough along its axis; a second elongated spindle core member coaxial with said first core member and being located apart from the same to form a space between said first and second core members, said second core member having an end portion located adjacent said first core member and formed with at least one cutout extending into said second core member from the end and side faces thereof adjacent said first core member; a tubular support member embracing said first and second core members and supporting the same, said tubular member being formed with at least one slot passing through the wall thereof and being aligned with said cutout of said second core member, said slot having an end portion extending beyond said cutout and opposite said space between said first and second core members, and said end portion of said slot being of a larger size than said cutout; and a centrally apertured ring member mounted in said tubular member in said space between said first and second core members, the aperture of said ring member being aligned with said bore of said first core member and overlapping said

be guided through said bore of said first core member, through said aperture of said ring member, through said cutout of said second core member and through said slot of said tubular support member, said aperture ring member having transverse to a line extending across said ring member and through said end portion of said slot cross sections which are all smaller than said end portion of said slot so that said ring member is insertable into and removable from said space between said core members through said end portion of said slot, and said aperture of said ring member having one end, located adjacent said first core member, of a smaller size than an opposite end of said aperture located adjacent said second core member, said aperture being smoothly curved between said ends thereof, and said ring member having a thickness which is smaller than the distance between said first and second core members, and said ring member being made of a ceramic material and having a smooth surface at least at said aperture thereof.

9. In a double twist spindle, in combination, a first elongated spindle core member formed with a bore extending therethrough along its axis; a second elongated spindle core member coaxial with said first core member and being located apart from the same to form a space between said first and second core members, said second core member having an end portion located adjacent said first core member and formed with at least one cutout extending into said second core member from the end and side faces thereof adjacent said first core member; a rotatably mounted tubular support member embracing said first and second core members and supporting the same for rotation therewith, said tubular member being formed with at least one slot passing through the wall thereof and being aligned with said cutout of said second core member, said slot having an end portion extending beyond said cutout and opposite said space between said first and second core members, and said end portion of said slot being of a larger size than said cutout; and a centrally apertured ring member mounted in said tubular member in said space between said first and second core members, the aperture of said ring member being aligned with said bore of said first core member and overlapping said cutout of said second core member so that a thread may be guided through said bore of said first core member, through said aperture of said ring member, through said cutout of said second core member and through said slot of said tubular support member, said aperture ring member having transverse to a line extending across said ring member and through said end portion of said slot cross sections which are all smaller than said end portion of said slot so that said ring member is insertable into and removable from said space between said core members through said end portion of said slot, and said aperture of said ring member having one end, located adjacent said first core member, of a smaller size than an opposite end of said aperture located adjacent said second core member, said aperture being smoothly curved between said ends thereof, and said ring member having a thickness which is smaller than the distance between said first and second core members.

10. In a double twist spindle, in combination, a first elongated, conical spindle core member formed with a bore extending therethrough along its axis; a second elongated, conical spindle core member coaxial with said first core member and being located apart from the same to form a space between said first and second core members, said second core member having an end portion located adjacent said first core member and formed with at least one cutout extending into said second core member from the end and side faces thereof adjacent said first core member; a conical, tubular support member embracing said first and second core members and supporting the same, said tubular member being formed with at least one slot passing through the wall thereof and being aligned with said cutout of said second core member, said slot having an end portion extending beyond said cutout and opposite said space between said first and second core members, and said end portion of said slot being of a larger size than said cutout; and a centrally apertured ring member mounted in said tubular member in said space between said first and second core members, the aperture of said ring member being aligned with said bore of said first core member and overlapping

said cutout of said second core member so that a thread may be guided through said bore of said first core member, through said aperture of said ring member, through said cutout of said second core member and through said slot of said tubular support member, said apertured ring member having transverse to a line extending across said ring member and through said end portion of said slot cross sections which are all smaller than said end portion of said slot so that said ring member is insertable into and removable from said space between said core members through said end portion of said slot.

11. In a double twist spindle, in combination, a first elongated spindle core member formed with a bore extending therethrough along its axis; a second elongated spindle core member coaxial with said first core member and being located apart from the same to form a space between said first and second core members, said second core member having an end portion located adjacent said first core member and formed with at least one cutout extending into said second core member from the end and side faces thereof adjacent said first core member; a tubular support member embracing said first and second core members and supporting the same, said tubular member being formed with at least one slot passing through the wall thereof and being aligned with said cutout of said second core member, said slot having an end portion extending beyond said cutout and opposite said space between said first and second core members, and said end portion of said slot being of a larger size than said cutout; and a centrally apertured ring member mounted in said tubular member in said space between said first and second core members, the aperture of said ring member being aligned with said bore of said first core member and overlapping said cutout of said second core member so that a thread may be guided through said bore of said first core member, through said aperture of said ring member, through said cutout of said second core member and through said slot of said tubular support member, said apertured ring member having transverse to a line extending across said ring member and through said end portion of said slot cross sections which are all smaller than said end portion of said slot so that said ring member is insertable into and removable from said space between said core members through said end portion of said slot and said ring member having an end portion located in said end portion of said slot and engaging said tubular member at said end portion of said slot thereof.

12. In a double twist spindle, in combination, a first elongated spindle core member formed with a bore extending therethrough along its axis; a second elongated spindle core member coaxial with said first core member and being located apart from the same to form a space between said first and second core members, said second core member having an end portion located adjacent said first core member and formed with at least one cutout extending into said second core member from the end and side faces thereof adjacent said first core member; a tubular support member embracing said first and second core members and supporting the same; said tubular member being formed with at least one slot passing through the wall thereof and being aligned with said cutout of said second core member, said slot having an end portion extending beyond said cutout and opposite said space between said first and second core members, and said end portion of said slot being of a larger size than said cutout; and a centrally apertured ring member mounted in said tubular member in said space between said first and second core members, the aperture of said ring member being aligned with said bore of said first core member and overlapping said cutout of said second core member so that a thread may be guided through said bore of said first core member, through said aperture of said ring member, through said cutout of said second core member and through said slot of said tubular support member, said ring member being rectangular in shape and having a width smaller than the width of said end portion of said slot so as to be insertable into and removable from said space between said core members through said end portion of said slot.

13. In a double twist spindle, in combination, a first elongated spindle core member formed with a bore extending therethrough along its axis; a second elongated spindle core member coaxial with said first core member and being located apart from the same to form a

space between said first and second core members, said second core member having an end portion located adjacent said first core member and formed with at least one cutout extending into said second core member from the end and side faces thereof of adjacent said first core member; a tubular support member embracing said first and second core members and supporting the same, said tubular member being formed with at least one slot passing through the wall thereof and being aligned with said cutout of said second core member, said slot having an end portion extending beyond said cutout and opposite said space between said first and second core members, and said end portion of said slot being of a larger size than said cutout; and a centrally apertured ring member mounted in said tubular member in said space between said first and second core members, the aperture of said ring member being aligned with said bore of said first core member and overlapping said cutout of said second core member so that a thread may be guided through said bore of said first core member, through said aperture of said ring member, through said cutout of said second core member and through said slot of said tubular support member, said ring member being rectangular in shape and having a width smaller than the width of said end portion of said slot so as to be insertable into and removable from said space between said core members through said end portion of said slot and said ring member having an end portion located in said end portion of said slot and engaging said tubular member at said end portion of said slot thereof.

14. In a double twist spindle, in combination, a first elongated spindle core member formed with a bore extending therethrough along its axis; a second elongated spindle core member coaxial with said first core member and being located apart from the same to form a space between said first and second core members, said second core member having an end portion located adjacent said first core member and formed with at least one cutout extending into said second core member from the end and side faces thereof adjacent said first core member; a tubular support member embracing said first and second core members and supporting the same, said tubular member being formed with at least one slot passing through the wall thereof and being aligned with said cutout of said second core member, said slot having a circular end portion extending across said space between said core members and overlapping the latter, said end portion of said slot being of a larger size than said cutout; and a centrally apertured ring member mounted in said tubular member in said space between said first and second core members, the aperture of said ring member being aligned with said bore of said first core member and overlapping said cutout of said second core member so that a thread may be guided through said bore of said first core member, through said aperture of said ring member, through said cutout of said second core member and through said slot of said tubular support member, said apertured ring member having transverse to a line extending across said ring member and through said end portion of said slot cross sections which are all smaller than said end portion of said slot so that said ring member is insertable into and removable from said space between said core members through said end portion of said slot.

15. In a double twist spindle, in combination, a first elongated spindle core member formed with a bore extending therethrough along its axis; a second elongated spindle core member coaxial with said first core member and being located apart from the same to form a space between said first and second core members, said second core member having an end portion located adjacent said first core member and formed with at least one cutout extending into said second core member from the end and side faces thereof adjacent said first core member; a tubular support member embracing said first and second core members and supporting the same, said tubular member being formed with at least one slot passing through the wall thereof and being aligned with said cutout of said second core member, said slot having a circular end portion extending across said space between said core members and overlapping the latter, said end portion of said slot being of a larger size than said cutout; and a centrally apertured ring member mounted in said tubular member in said space between said first and

second core members, the aperture of said ring member being aligned with said bore of said first core member and overlapping said cutout of said second core member so that a thread may be guided through said bore of 5 said first core member, through said aperture of said ring member, through said cutout of said second core member and through said slot of said tubular support member, said apertured ring member having transverse to a line extending across said ring member and through said end portion 10 of said slot cross sections which are all smaller than said end portion of said slot so that said ring member is insertable into and removable from said space between said core members through said end portion of said slot and said ring member having an end portion located in said 15 end portion of said slot and engaging said tubular member at said end portion of said slot thereof.

16. In a double twist spindle, in combination, a first elongated spindle core member formed with a bore extending therethrough along its axis; a second elongated spindle core member coaxial with said first core member and being located apart from the same to form a space between said first and second core members, said second core member having an end portion located adjacent said first core member and formed with at least one 20 cutout extending into said second core member from the end and side faces thereof adjacent said first core member; a tubular support member embracing said first and second core members and supporting the same, said tubular member being formed with at least one slot passing 25 through the wall thereof and being aligned with said cutout of said second core member, said slot having a circular end portion extending across said space between said core members and overlapping the latter, said end portion of said slot being of a larger size than said cutout; and a centrally apertured ring member mounted in 30 said tubular member in said space between said first and second core members, the aperture of said ring member being aligned with said bore of said first core member and overlapping said cutout of said second core 35 member so that a thread may be guided through said bore of said first core member, through said aperture of said ring member, through said cutout of said second core member and through said slot of said tubular supporting member, said ring member being rectangular in 40 shape and having a width smaller than the width of said end portion of said slot so as to be insertable into and removable from said space between said core members through said end portion of said slot.

17. In a double twist spindle, in combination, a first
50 elongated spindle core member formed with a bore ex-
tending therethrough along its axis; a second elongated
spindle core member coaxial with said first core mem-
ber and being located apart from the same to form a
55 space between said first and second core members, said
second core member having an end portion located adja-
cent said first core member and formed with at least one
cutout extending into said second core member from the
end and side faces thereof adjacent said first core mem-
ber; a tubular support member embracing said first and
60 second core members and supporting the same, said tubu-
lar member being formed with at least one slot passing
through the wall thereof and being aligned with said
cutout of said second core member, said slot having a
circular end portion extending across said space between
65 said core members and overlapping the latter, said end
portion of said slot being of a larger size than said cut-
out; and a centrally apertured ring member mounted in
said tubular member in said space between said first and
second core members, the aperture of said ring mem-
70 ber being aligned with said bore of said first core mem-
ber and overlapping said cutout of said second core
member so that a thread may be guided through said
bore of said first core member, through said aperture
of said ring member, through said cutout of said second
75 core member and through said slot of said tubular sup-
porting member, said ring member being rectangular in
shape and having a width smaller than the width of said
end portion of said slot so as to be insertable into and
removable from said space between said core members
80 through said end portion of said slot and said ring
member having an end portion located in said end por-
tion of said slot and engaging said tubular member at
said end portion of said slot thereof.
